UNITED STATES PATENT OFFICE.

ROBERT FRANZ WERK, OF NEW ORLEANS, LOUISIANA.

OIL-PRESS MAT.

SPECIFICATION forming part of Letters Patent No. 758,574, dated April 26, 1904.

Original application filed September 10, 1901, Serial No. 74,906. Divided and this application filed June 26, 1902. Serial No. 113,265. (No model.)

To all whom it may concern:

Be it known that I, ROBERT FRANZ WERK, a citizen of the United States, and a resident of New Orleans, in the parish of Orleans and State of Louisiana, have invented new and useful Improvements in Oil - Press Mats, of which the following is a full, clear, and exact description.

My invention relates to improvements in oil-press mats or cloths; and it constitutes a division of a prior application for Letters Patent of the United States, filed by me on September 10, 1901, Serial No. 74,906.

The improved mat of this invention is characterized by an increased pliability in the warp threads or strands forming an integral part of a hair press cloth or fabric. Articles of this character are preferably made of hair - warp and hair-weft interwoven together, because hair strands afford good drainage for the oil and impart a glossy surface to the fabric, that enables the cake to be introduced with facility and the article to be stripped with ease from the compressed material. The pliability of the fabric, cloth, or mat is attained by the admixture of soft hair with long coarse hair in the warp-threads. The weft-threads of the improved mat are protected by the warp-threads against the shearing strain exerted by the pressure of the seeds, so that the mat is not liable to split in a longitudinal direction, and at the same time the mat is capable of folding longitudinally at any line without breaking. The selvage of the mat presents a yielding cushion, which prevents the article from giving way under pressure and minimizes unraveling of the threads.

The invention consists of an oil-press mat comprising warp-threads and weft-threads, both composed of long animal-hair, said warp-threads consisting of hard, stiff, and coarse hair mixed with soft pliable hair and the weft-threads consisting of soft pliable hair, said warp-threads exceeding in number per square inch the weft-threads and disposed in close proximity to each other to conceal and protect the weft-threads, the warp-threads forming the selvage consisting of soft pliable hair and the said weft-threads of soft pliable hair being thicker than the said warp-threads.

Reference is to be had to the accompanying drawings, forming a part of this specification, in which similar characters of reference indicate corresponding parts in both the figures.

Figure 1 is a plan view of an oil-press cloth 55 constructed in accordance with this invention, and Fig. 2 is a longitudinal section thereof on the line 2 2 of Fig. 1.

The fabric of the present invention is necessarily made of animal-hair; and it consists 60 of warp-threads A B in the body portion and at the selvage, respectively, of the fabric and the weft-threads C, which are interwoven with said warp-threads in a way to be concealed and protected thereby. To secure the desired 65 flexibility of the fabric in a transverse direction, I employ warp-threads A, which consist of hard, stiff, and coarse hair mixed with soft pliable hair. The two kinds of hair are preferably quite long, and they are mixed 70 together in the proper proportions, after which the hairs are twisted or spun together, so as to secure a strand or thread of the proper length and thickness. The warp-threads C are composed of long animal-hair, which is 75 soft and pliable, and this hair after having been selected and prepared in a suitable way is twisted and spun to secure a strand or thread having the proper length. I prefer to make the weft-threads C of increased thickness 80 as compared with the warp-threads A B in the body and selvage of the fabric, the warp-threads B which are to be used in making the selvage of the fabric consisting of soft pliable hair which is spun in a manner similar 85 to the threads of the weft C.

After preparing the threads or strands the fabric is woven by arranging the warp A B parallel with each other and in the same transverse plane, while the weft C is arranged 90 transversely across the warp-threads in a manner to be interlaced therewith. The warp-threads through the body portion of the selvage greatly exceed the number of the weft-threads, and I prefer to employ from five to 95 eight times as many of the warp-threads per square inch as the weft-threads, thus making the warp-threads afford the desired protection to the weft-threads. The use of the weft-threads made of soft hair and of increased 100

thickness as compared with the warp-threads makes the weft-threads afford a desirable cushion to the warp-threads, thus reducing the liability of the warp-threads to cut or sever 5 the weft when the mat is exposed to the pressure of a press. The employment of soft hair in the warp-threads secures a greater degree of pliability in the fabric than can be attained by making the warp and weft of hard coarse 10 hair, and at the same time the mat possesses good drainage qualities. After it shall have been in use a short time the surface of the mat becomes glossy, the latter being advantageous because it facilitates the introduction 15 of the formed cake into the press and enables the mat to be stripped with ease and facility from the compressed material. By protecting the weft-threads, owing to their being inclosed by the warp-threads, the seeds cannot 20 penetrate and injure the weft-threads, and at the same time the mat can be folded longitudinally without breaking or giving way in any of its threads.

Having thus described my invention, I claim 25 as new and desire to secure by Letters Patent—

1. An oil-press mat or cloth made entirely of long animal hair and consisting of warp and weft threads, said weft-threads being composed exclusively of soft, pliable hair and the

warp-threads greatly exceeding the weft- 30 threads in number per square inch.

2. An oil-press mat consisting of warp-threads and weft-threads, both composed of long animal hair, said warp-threads consisting of hard, stiff and coarse hair mixed with soft 35 pliable hair, and the weft-threads consisting of soft pliable hair; said warp-threads exceeding in number per square inch the weft-threads, and arranged in close proximity to each other so as to conceal and protect the 40 weft-threads; the warp-threads forming the selvage consisting of soft pliable hair, and said weft-threads of soft pliable hair being thicker than the warp-threads.

3. An oil-press mat consisting of hair warp- 45 threads and hair weft-threads, the warp-threads being composed of hard, stiff and coarse hair mixed with soft, pliable hair, and the weft-threads being composed of soft, pliable hair, the selvage of the mat being formed 50 by warp-threads of soft, pliable hair.

In testimony whereof I have signed my name to this specification in the presence of two subscribing witnesses.

ROBERT FRANZ WERK.
